UNITED STATES PATENT OFFICE.

HARMAN GREENBERG, OF HUNTINGDON, PENNSYLVANIA.

POCKET FOR VESTS.

SPECIFICATION forming part of Letters Patent No. 431,050, dated July 1, 1890.

Application filed March 18, 1890. Serial No. 344,429. (No model.)

To all whom it may concern:

Be it known that I, HARMAN GREENBERG, a citizen of the United States, residing at Huntingdon, in the county of Huntingdon and 5 State of Pennsylvania, have invented certain new and useful Improvements in the Construction of the Pockets of a Gentleman's Vest or Waistcoat; and I do hereby declare that the following is a full, clear, and exact 10 description of the invention, which will enable others skilled in the art to which it appertains to make and use the same.

My invention relates to improvements in the pockets of a gentleman's vest or waistcoat, 15 and the objects are to secure greater safety for his watch and at the same time preserve the ordinary display of the watch chain or guard. I attain these objects by the arrangement illustrated in the accompanying drawings.

Figure 1 represents a front view of a high-cut vest or waistcoat; Fig. 2, a front view of a low-cut or dress vest or waistcoat, and Fig. 3 a vertical view of the section marked XX 25 in Fig. 2.

Inside the vest or waistcoat is attached a watch-pocket (marked B,) which may be of the same size as the outer ordinary pocket,

(marked A,) or it may be smaller. The inner pocket B is not accessible in a high-cut vest 30 or waistcoat without opening the garment, and in a dress vest or waistcoat without inserting the hand between the vest or waistcoat and the body. This inner pocket B is placed immediately behind the outer pocket, and a button-hole or slot (marked E) in the material permits the watch-chain to be drawn through from the inside and the hook or bar attached to the button-holes in front in the manner that watch-chains are usually worn. The slot or 35 button-hole E should be cut below the upper edge of the outer pocket, so as to be invisible except by pulling the outer pocket down. The same device may be attached to the upper pocket and to all the pockets of the vest. 40 45

What I claim is—

A garment having a pocket opening upon the outside thereof and a pocket opening upon the inside, said pockets communicating by a button-hole or small opening for the 50 passage of a watch-chain, substantially as and for the purposes shown and described.

HARMAN GREENBERG.
